US0D1061886S

(12) **United States Design Patent** (10) Patent No.: **US D1,061,886 S**
(45) Date of Patent: ** Feb. 11, 2025

(54) **TONGUE SCRAPER**

(71) Applicant: **Sacks Holdings, Inc.**, San Diego, CA (US)

(72) Inventor: **Devin S. Chodorow**, San Diego, CA (US)

(73) Assignee: **Sacks Holdings, Inc.**, San Diego, CA (US)

(**) Term: **15 Years**

(21) Appl. No.: **29/877,495**

(22) Filed: **Jun. 7, 2023**

Related U.S. Application Data

(63) Continuation of application No. 29/796,988, filed on Jun. 28, 2021, now Pat. No. Des. 992,734.

CLAIM

The ornamental design for tongue scraper as shown and described.

DESCRIPTION

FIG. 1 is a perspective view of a tongue scraper showing my new design;

FIG. 2 is a top plan view thereof;

FIG. 3 is a bottom plan view thereof;

FIG. 4 is a front plan view thereof;

FIG. 5 is a back plan view thereof;

FIG. 6 is a left plan view thereof; and,

FIG. 7 is a right plan view thereof.

The broken lines shown in FIGS. 1-7 illustrate portions of the tongue scraper that form no part of the claimed design.

1 Claim, 5 Drawing Sheets
